ELECTRIC RELAY.

1,228,097.

Specification of Letters Patent.

Patented May 29, 1917.

Application filed May 14, 1912, Serial No. 697,148. Renewed October 30, 1916. Serial No. 128,638.

To all whom it may concern:

Be it known that I, JAMES B. CRIPPEN, a citizen of the United States of America, and a resident of Chicago, county of Cook, 5 and State of Illinois, have invented a new and useful Improvement in Electric Relays, of which the following is a specification.

My invention pertains to electric relays. My object is to produce an electric relay 10 which (a) will have a tensionless armature with but two positions of rest, (b) will reverse the position of its armature when influenced by a brief current flowing through its controlling helix in a predetermined or 15 first direction, (c) will maintain its armature in either position indefinitely when not influenced by line currents, and (d) will maintain its armature at rest in either position despite the influence of current 20 through its line helix in the reverse or second direction. My relay is designed primarily for use in systems of printing telegraphy, but its use is not necessarily so limited.

25 I provide a polarized relay having an electromagnetic field, and therefore having both line and field helices, the line helix being the helix for controlling the movements of the armature. In this relay, I provide contacts 30 upon the armature for reversing the direction of the electric current through the field helix, whereby by the movement of the armature the magnetic polarization of the field is reversed. In addition, I provide 35 upon the armature such electric contact elements as may be required to operate local or controlled circuits. The arrangement of parts thus attained reverses the polarization of the magnetic field of the relay whenever 40 the armature is reversed in position, thus reversing the polar condition of the relay with reference to the line, so that, instead of requiring a reverse current to return the armature to its initial position, it requires another impulse of current in the same direction as that which moved the armature from 45 its initial position.

In the drawings, Fig. 1 shows an elevation of my relay. Fig. 2 shows a diagram of 50 the magnetic and electric elements. Fig. 3 shows a modification. In these figures, like numerals refer to like parts throughout.

Upon the yoke 1, the magnets 2 and 3 and the helix 4 are rigidly mounted. The core-

55 armature 5 is pivoted upon the yoke 1 and is positioned within the helix 4. The helix 4 is the field helix; the helices 21 and 31 60 jointly, form the line helix or controlling helix of the relay. The yoke, cores and armature are of soft iron, substantially without permanent magnetism, acquiring all their magnetic qualities from the currents flowing in the helices associated with them.

The helices 21 and 31 are so connected 65 in the line wire 6—6' that when a current flows in the wire 6—6' the magnets 2 and 3 will present poles of opposite magnetic polarity to the core-armature 5. As the part 5 also is polarized by current through the helix 4, the polarity of the part 5 will cause 70 it to repel one and attract the other of the poles presented by magnets 2 and 3.

At this point in the description, it becomes obvious that the part 1 acts magnetically only to influence the efficiency of the 75 relay, since all the functions described would be attained if the part 1 were omitted or if the part 1 were made of non-magnetic material, acting as a mechanical support only.

80 As Fig. 2 is drawn, the relay is adjusted to reverse its armature in response to an impulse of positive current from 6 to 6' in the line conductor. As the figure is drawn, current flows from positive pole of battery 7 85 through contact 9 and armature 5 and upward through helix 4, producing a south magnetic pole at the free end of the armature 5. This polarization will cause the free-end of the armature 5 to attract the nearer 90 of the two free poles of magnets 2 and 3, resulting in holding the armature motionless when not influenced by line currents. A current in the line conductor flowing from 6' to 6 will produce a south pole at the free 95 end of magnet 3 and a north pole at the free end of magnet 2, thus attracting the armature 5 toward core 2 and repelling it from the core of magnet 3. The armature 5 will remain motionless under the influence of 100 such a current, corresponding to the current of the second direction as mentioned in the preliminary description of this specification.

A current in the line conductor flowing 105 from 6 to 6' will produce a south pole on the free end of magnet 2 and a north pole on the free end of magnet 3, repelling 5 from 2 and

attracting 5 toward 3, moving 5 and changing its electrical contact engagement from 9 to 10, breaking the circuit of 4 and 7 and closing a circuit including 4 and 8. By this change, current is permitted to flow through battery 8 from its positive pole, upward through a connecting conductor and then downward through the helix 4, thence through 5 and 10 to the negative pole of battery 8. This current reverses the magnetic polarity of armature 5, producing a north pole at its free end. By this time, that is, by the time of the completion of the reversal of the polarization of the armature 5, or very soon thereafter, the line current influencing the armature to reverse its position should have ceased and the core of magnet 3 should have become neutral (or reversed under the influence of current in helix 4) so that the armature 5 will attract that core and will maintain its new position against the magnet 3 until a subsequent impulse in the same direction operates to restore the armature 5 to its initial position.

The subsequent impulse, flowing from 6 to 6' in the line conductor, produces as before a south pole on the free end of the core of magnet 2 and a north pole on the free end of the core of magnet 3. As the free end of armature 5 now is north, 5 will be attracted by 2 and repelled by 3, resulting in its movement back to its initial position, with incidental reversal of its polarity, so that the next subsequent line current from 6 to 6' will reverse it, but all line currents from 6' to 6 will leave it motionless.

It becomes manifest that a long continued current from 6 to 6' will result in a buzzing or continued vibration of the armature 5.

Preferably, the armature 5 is reversed by impulses uniform in duration. That the armature 5 may swing at a speed in keeping with its controlling impulses, I may provide

an adjusting means, such as 11 of Fig. 3, which shows an adjustable weight upon a 45 pendulum armature. The magnetic lag of the relay also contributes to the limitation of the duration of the controlling impulse, and offers a further method of adjustment.

The contacts for controlled circuits may be 50 carried by the armature 5 in any desired manner. In Fig. 2 I show a set of three contact elements, 12, 13, 14, the element 13 being reached electrically by a flexible tensionless conductor from the fixed binding post 13'; 55 in Fig. 3 I show the contact elements upon opposite ends of the armature.

In mechanical embodiment, the form of my improved relay may be varied greatly.

What I claim as new and desire to obtain 60 by United States Letters Patent is:

1. In an electric relay, an armature, a polarizing coil surrounding a portion of said armature, a pair of actuating coils each adjacent to said armature and not in electric 65 contact with said polarizing coil, and means for reversing the direction of current flow through said polarizing coil when said armature is actuated by said actuating coils.

2. In an electric relay, an armature, a 70 polarizing coil for said armature, a source of current for energizing said coil, a pair of armature actuating coils, a separate source of alternating current for energizing said actuating coils, and means for reversing the 75 direction of current flow through said polarizing coil when said armature is actuated by said actuating coils.

Signed by me at Chicago, county of Cook and State of Illinois, in the presence of two 80 witnesses, this 14th day of July 1911.

JAMES B. CRIPPEN.
